CARPENTER'S LAYOUT TOOL

William Sigggson, Philadelphia, Pa.

Application December 18, 1952, Serial No. 326,683

6 Claims. (Cl. 33—94)

1

My invention relates to a combination carpenter's tool, and more particularly to improvements in a combination carpenter's tool embodying a framing square, universal square, protractor, bevel square, plumb and level tool, and center guages whereby stair horse lay-outs, skirting board lay-outs and roof pitch lay-outs may be readily and easily made. This application is a continuation in-part of my co-pending application Serial No. 145,290, and now abandoned.

Prior to the present invention, combination square and protractors have been manufactured and used, but heretofore, no square has been used which is readily adaptable for use by the novice by simplifying stair horse lay-outs, roof framing pitch lay-outs, and all roof coverings. Carpenters in the past have found it relatively difficult to obtain roof framing pitches as well as the complementary angles thereof. With my invention, I am able to use one indicia embodied together with my square so that roof framing pitches and their complementary angles can be easily and readily ascertained by a novice.

It, therefore, is an object of my invention to provide a square which will embody a bevel square, try square, break down framing square, combination square, protractor, level and plumb, lay-out tool for jambs, simplified tool for marking out hardware, centering tool for 2 x 4, 2 x 6, and 2 x 8's, center finder for various door thicknesses, unique tool for stair building, a tool for readily obtaining roof framing pitches, partition lay-out tool, and a beam compass.

Another object of my invention is to provide a device than can be used for any purpose a carpenter's square can be used.

Another object of my invention is to provide an instrument to lay out stair horses and roof framing pitches without laborious calculations, charts, and reference books.

Another object of my invention is to provide an instrument of the type herein described which is simple to use.

Another object of my invention is to provide a tool that is light, easily foldable and simple to store and carry about, saving space and lightening the mechanic's tool box.

Other objects of my invention are to provide a device of the character described, which is sturdy in construction, economical to produce, and highly effective in operation.

With the above and related objects in view, my invention consists in the details of construction, and combination of parts, as will be more fully understood when the description is ready in

2

conjunction with the accompanying drawings, in which:

Fig. 1 is a face view of a combined square, bevel, plumb and level as embodied in my invention.

Fig. 2 is a side view of a combined square, bevel, plumb and level as embodied in my invention.

Fig. 3 is a perspective view of a fragmentary portion of the device embodying my invention.

Fig. 4 is a fragmentary perspective view of the device embodying my invention.

Fig. 5 is a sectional view taken along the lines 5—5 of Fig. 1.

Fig. 6 is a sectional view taken along the lines 6—6 of Fig. 4.

Fig. 7 is a sectional view taken along the lines 7—7 of Fig. 1.

Fig. 8 is a perspective view of the disc indicator and mounting block used in determining the roof pitches in angles.

Fig. 9 is a perspective view of the short removable arm which is always at right angles to the body.

Fig. 10 is a perspective view of the holder for the indicator discs.

Fig. 11 is a perspective view of the bolt and nut used to secure the adjustable blade to the handle.

Fig. 12 is a face view of the lay out tool as used for scribing stair skirting.

Fig. 13 is an enlarged fragmentary face view of the tool illustrated in Fig. 12.

Fig. 14 is a fragmentary sectional view taken on line 14—14 Fig. 13.

Fig. 15 is a transverse sectional view taken on line 15—15, Fig. 13.

Fig. 16 is a sectional view taken on line 16—16, Fig. 15.

Fig. 17 is a perspective view of the guide member which is secured to the rear of the tool body and rests on the upper surface of the skirt board.

Fig. 18 is a face view of the layout tool and attachments used for scribing stair horses.

Fig. 19 is an enlarged face view of the tool illustrated in Fig. 18.

Fig. 20 is an enlarged fragmentary sectional view taken on line 20—20, Fig. 19.

Fig. 21 is a rear view of the arm used for scribing the tread of the stair horse illustrating the markings for indicating the length of the tread, and,

Fig. 22 is a fragmentary view of the disc used for determining the height of the riser.

Referring now to the drawings and particu-

larly Fig. 1, a carpenter's layout tool made in accordance with the present invention comprises a body portion or head generally designated as A, an adjustable blade, generally designated as B, attached to the body A, and a short removable arm, generally designated as C, which can be used to get the complementary angles of plumb cuts.

In order to obtain the proper angle for the pitch of a roof, a disc, generally designated as E, is provided. The disc E has impressed on its face indicia 10. Various discs are provided and stored in a holder at the base of the body portion A as seen in Fig. 10, which comprises a pair of cylindrical openings 11 and 12 having a sliding cover 13 held in position by a pair of bolts 14, 14.

It is apparent that the blade B and the disc E must move in unison and that the disc E must occupy a predetermined position with respect to the body A to carry out the objects of my invention.

To achieve this unison of movement and predetermined positioning of the disc, there is provided in the body A, a large cylindrical bore 17 extending only a portion of the distance through the body A and a smaller cylindrical bore 19 concentrically aligned with the said first bore, forming an annular seat 19a in the body A parallel to the face of body A. A first annular bushing 19b is provided for the bore 19, said bushing being a press fit and smaller in height than the bore 19. There is also provided a second annular bushing 17a for the bore 17 which has freedom of movement and extends above the face of the body A. The bushing 17a is provided with a centrally positioned rectangular bore 17c. Bushing 19b has an annular bore concentrically aligned with bushing 17a, for accommodating a bolt D. The bushing 17a is also provided with a small bore 17b for inserting a pin therein. The small bore 17b is located adjacent the rectangular bore 17c.

The bolt D which has a head 20 with a pair of parallel sides 20a and 20b adapted to fit in the slot B1 in the blade B. The shank 21 of the bolt D is of rectangular formation and it is attached rigidly to the head 20 of the bolt D so that rotation of the head 20 carries with it the shank 21. The bolt D is inserted in the rectangular bores of the aforementioned bushings. The free end of the bolt D is provided with a series of threads, which are adapted to engage with the thumb nut 22.

The disc E has a centrally positioned rectangular opening 24 which snugly fits over the shank of the bolt D. The disc E is also provided with a small circular opening 25 in alignment with bore 17b in the bushing 17a. A pin 26 is inserted through the opening 24 in the bore 17b, thereby positioning the disc E properly with respect to the body A and the blade B. The thumb nut 22 is then threaded upon the free end of the bolt D. When the thumb nut 22 is tightened, it locks the disc E by forcing the bushing 17a against the shoulder 19a, while the parallel sides 20a and 20b of the head 20 in the slot B1 prevents the blade B from moving. Thus it can be seen that the movement of the blade B is imparted to the head 20 which carries the shank 21, which in turn carries the bushings 17a, 19b and the disc E.

A selection of discs E is provided for different purposes. These discs are stored in the holders 11 and 12 as previously described. In use the proper disc is selected for the job to be done and placed on the shank 21 of the bolt D with the

opening 24 of the disc E in alignment with the bore 17b of the bushing 17a. The pin 26 is positioned therein, and the thumb nut 22 is threaded upon the free end of the bolt D. The blade B is then moved until the notation on the indicia 10 for a particular operation of the job is aligned with a signal marker on the body A, whereupon it is locked in place by tightening the thumb nut 22 on the bolt D. Once the instrument has been set to an angle, the complement thereof can be readily ascertained or marked off by using the short removable arm C in place of the body A. Both angles are marked along the blade B.

When the shorter arm C and the blade B are at right angles to the body A as shown in full lines in Fig. 1, the instrument can be used for the layout of jambs, nite latches and centers for 2x4, 2x6, and 2x8's, the markings for same being provided on the removable arm C, at 30 (Fig. 9). Such graduations may be readily made at a predetermined distance from the shoulder on the arm C that abuts the sides of body A. Various scales and markings are provided on the face of the body A such as hundredths of a foot and hundredths of an inch, designated at 32.

Architect's standard hinge size and hinge setting markings are provided on the side of the body A at 34 making it easy for the novice to layout door hinges properly.

A slot 36 is provided at the rear face of the body A, for accommodating various accessories, such as depth gauges, increasing the utility of my tool tremendously.

My device may be closed by loosening the thumb nut 22 and knifing the blade B into the slot 38 in the side of the body A. When closed my device may be used as a level or plumb tool in the ordinary manner by virtue of the level indicators recessed in the side, and the plumb indicators recessed in the face of the body A. The level 39 and the plumb 40 are best illustrated in Fig. 4.

Figs. 12 to 17, inclusive, illustrate the use of the carpenter's layout tool of the present invention, with various attachments, for scribing a skirting board for stairways. With reference to Fig. 12, a skirt board 41 is temporarily supported in position immediately above a set of steps 42 and the carpenter's layout tool of the present invention is slidably mounted on the skirt board in engagement with the steps in order to scribe the outline of the steps on the skirt board to permit the skirt board to be cut to fit the contour of the steps.

To use the carpenter's layout tool to mark a skirt board, an adaptor block 43 is fastened to the rear of the tool body A and slidably mounts a guide blade 44 which has an inturned end portion 44a thereon adapted to engage and follow the outline of the steps. A relatively wide angular slot 45 extends across the adaptor block 43 and receives a guide block 46 which is rotatably mounted on the adaptor block 43 by a bolt 47 having an enlarged head portion 47a thereon. A groove 48 is provided in the rotatable guide block 46 which slidably receives the guide block 44.

In accordance with the present invention the adaptor block 43 is secured to the rear of the tool body A with the guide blade mounted in the groove 48 between the adaptor block and the tool body. This is accomplished by inserting the head of the bolt 47 in the tool body slot 36 and tightening a thumb nut 51 on the bolt to maintain the bolt and adaptor block in position. A pair of lugs 52, 52 extending outwardly from the face of the adaptor block at opposite ends thereof

engage the slot 36 and maintain the block in a predetermined position parallel with the tool body. The tool body is then placed on the upper surface of the skirt board as shown in Fig. 12 with the guide blade in a vertical position and the thumb nut 51 is then securely tightened to prevent rotary movement of the guide block 46 and maintain the blade in the vertical position. An elongated slot 50 centrally of the guide blade permits the guide blade to be moved vertically with respect to the tool body A and thereby follow the outline of the steps by sliding the tool body along the skirt board while at the same time the guide blade 44 is moved vertically with its pointer 44a in engagement with the steps.

In order to mark the outline of the steps on the skirt board, a tool or pencil holder 53 is provided mounted in a longitudinal slot 54 on the guide blade 44. The tool or pencil holder 53 has an opening 55 therethrough extending perpendicular to the guide blade in which a pencil 56 or other marking tool may be inserted. A thumb bolt 57 is inserted into the holder 53 in engagement with the pencil or marking tool as illustrated in Fig. 15 to secure the pencil or marking tool in the holder. The holder 53 is secured to the guide blade at a predetermined distance above the point of the guide blade equal to the height of the rise of the steps so that as the point of the guide blade follows the outline of the steps, the pencil or marking tool in the holder 53 will copy the outline of the steps on the skirt board.

Figs. 18 to 22, inclusive, of the drawings illustrate the use of the carpenter's layout tool of the present invention for marking a stair horse prior to cutting. In this embodiment of the present invention a removable blade 58 is provided which may be secured to the lower end of the blade B at right angles thereto by means of a clamp 59 secured to the blade B by a wing nut 61. The upper end of the clamp 59 is provided with a downwardly and inwardly extending lip portion 62 which extends into a beveled slot 63 in the removable blade 58 to tightly hold the blade 58 against the end of the blade B. By changing the position of the clamp 59 in the slot 63, the relative position of the removable blade 58 with respect to the blade B may be varied.

In order to mark the stair outline on the stair horse, the adjustable blade B is positioned at an acute angle with respect to the tool body A with one end thereof projecting downwardly a distance equal to the length of the stair tread. Marks on the inner surface of the blade B as indicated at 64 in Fig. 21 may be used to determine the amount of projection of the blade B. The disc E1 which is rotatable with the blade B is set to indicate the height of the rise of the steps in inches and the removable blade 58 is then secured to the blade B in the manner previously described with the inner end thereof extending into the longitudinal slot in the tool body. The tool body is then positioned against the edge of the stair horse with the two blades, B and 58, in engagement with the stair horse as illustrated in Fig. 18 and a pencil or other marking device is used to mark the outline of the stairs on the stair horse.

From the foregoing, it will be observed that the present invention provides a novel layout tool which is of a relatively simplified construction and which has a greater variety of uses.

While particular embodiments of the present invention have been illustrated and described herein, it is not intended to limit the invention

to such a disclosure and changes and modifications may be incorporated and embodied therein in when in the scope of the following claims.

I claim:

- 5 1. In a carpenter's layout tool, a body having a pair of parallel faces and a pair of parallel sides and a bore at one end, a movable blade with a slot therein, a relatively short abutment detachably mounted in the body at right angles thereto and adjacent the pivot of the movable blade, a disc having indicia thereon to indicate the angle between the body and the blade, a bolt to hold said disc and said movable blade in fixed relationship to each other, said bolt securing said blade and said disc to said body member by passing through said bore, and a thumb nut on said bolt to lock said movable blade and said disc in any relationship to said body.
- 10 15 2. A carpenter's combination square comprising a body member, walls on said body member defining a longitudinal groove, a slotted blade pivotally mounted at one end of the body member positioned to telescope into said groove, walls defining at least one groove at right angles to the centerline of the body member and adjacent the pivot point of the blade, and an abutment positioned to slidably engage said last-named walls and to cooperate with the blade for positioning the blade at right angles to the body member yet permitting slidable movement between the blade and the body member.
- 20 25 30 35 3. A structure in accordance with claim 2, in which the abutment comprises a blade slidably in the body member, and an offset portion secured to said blade, said offset portion having a stop to limit slidable movement of the abutment in the body member.
- 40 45 50 55 4. A carpenter's layout tool comprising a body member, walls on said body member defining a longitudinal groove, a slotted blade pivotally mounted at one end of the body member positioned to telescope into said groove, walls defining a second groove at right angles to the center line of the body member adjacent the pivot point of the blade, an abutment positioned to engage the second groove and to cooperate with the blade for positioning the blade at right angles to the body member yet permitting slid- able movement between the blade and the body member, walls defining a third groove longitudinally of said body member, an adapter block positioned in engagement with said third groove and secured to said body member, a guide blade carried by said adapter block at an acute angle to said body member and mounted for relative vertical sliding movement in said adapter block, and a marking tool carried by said guide blade.
- 60 65 70 75 5. A carpenter's layout tool comprising a body member, walls on said body member defining a longitudinal groove, a slotted blade pivotally mounted at one end of the body member positioned to telescope into said groove, walls defining a second groove at right angles to the center line of the body member adjacent the pivot point of the blade, an abutment positioned to engage the second groove and to cooperate with the blade for positioning the blade at right angles to the body member yet permitting slid- able movement between the blade and the body member, walls defining a third groove longitudinally of said body member, an adapter block positioned in engagement with said third groove and secured to said body member, a rotatable guide block carried by said adapter block, a

guide blade mounted in said guide block for relative sliding movement therein; locking means to secure said guide block in any desired position with respect to said adapter block with the guide blade positioned at an acute angle to the body member, and marking means carried by said guide blade;

6. A carpenter's layout tool comprising a body member, walls on said body member defining a longitudinal groove, a slotted blade pivotally mounted at one end of the body member positioned to telescope into said groove, walls defining at least one groove at right angles to the center line of the body member adjacent the

pivot point of the blade, an abutment positioned to slidably engage said last named walls and to cooperate with the blade for positioning the blade at right angles to the body member yet permitting slidable movement between the blade and the body member, means to position said blade at any desired acute angle with respect to said body member, a second blade, and means to secure the second blade at right angles to said first blade with one end thereof extending into the longitudinal groove in said body member.
